UNITED STATES PATENT OFFICE.

OCTAVE J. ST. PIERRE, OF CHICAGO, ILLINOIS.

GAME

1,396,073.

Specification of Letters Patent.

Patented Nov. 8, 1921.

Application filed January 24, 1920. Serial No. 353,701.

To all whom it may concern:

Be it known that I, OCTAVE J. ST. PIERRE, a subject of the King of England, and a resident of the city of Chicago, in the county 5 of Cook and State of Illinois, have invented certain new and useful Improvements in a Game; and I do hereby declare that the following is a full, clear, and exact description of the same, reference being had to the accompanying drawings, and to the numerals of reference marked thereon, which form a part of this specification.

This invention relates to a game adapted to be played by young or old people, and, according to its size, to be used either out-of-doors or indoors.

The invention has for its object the provision of a target of the proportions and representation of a pool table which is 20 adapted to be hung upon a wall or other suitable means and toward which objects are projected in the form of darts by any suitable means to leave a mark or impression upon the target and with the target having 25 permanently marked thereon an arrangement of squares and circles representing pool balls and various possibilities of plays with reference thereto according to impressions made upon the target by the darts.

30 Other and further important objects of this invention will be apparent from the disclosures in the drawings and specification.

The invention (in a preferred form) is 35 illustrated in the drawings and hereinafter more fully described.

Drawings.

Figure 1 is a plan view of a target of the 40 game embodying the principles of my invention.

Fig. 2 is an elevation of a dart-projecting device.

Fig. 3 is a side elevation thereof.

Fig. 4 is a top view thereof.

Fig. 5 is a view of one of the darts.

Fig. 6 is an elevation of a strip of cloth.

Fig. 7 is modified form of dart.

Fig. 8 is an edge view of the target.

Description.

The game consists of a target 1 of the proportionate dimensions of a pool table, and having marked upon the surface thereof 55 within the confines of the sides of the target sixteen squares 2 each having a pair of con-

centric circles 3 therein to represent balls. Fifteen of the concentric pairs of circles are marked with the numerals one to fifteen inclusive as shown, and the sixteenth pair 60 of circles substantially at the center of the target are marked with the word "Cue". Small circles 4 are inscribed at the point of intersection of the squares occupied by the balls 2—3—9—12 and 3—4—12—9 and 65 10—13—5—6 and 13—11—6—7.

Darts are used, which in the terms and description of the game are described as "cues", having the reference numeral 5 and each of these, as shown in Fig. 5, is provided with a notch 6 and is shaped and balanced for true flight through the air. The head of the dart is denoted by the reference numeral 7 and may be of soft semiyieldable material to receive chalk thereon so that 75 the dart striking the target will leave a chalk impression at its point of contact. Any means whatsoever may be provided for projecting the dart toward the target or the darts may be thrown by hand. However, I 80 have shown a simple form of slingshot 8 having any suitable elastic 9 secured or attached thereon in any suitable manner and adapted to be engaged by the notch 6 of a dart and then stretched by hand and upon 85 release of the dart throwing the same toward the target.

In Fig. 7 I have shown a strip of cloth 10 attached to the tail of the dart 5 by any suitable means and this cloth may have a 90 distinctive color to identify the dart and also said cloth serves as a guiding means for the dart in flight.

Operation.

As stated, the target 1 may be of any convenient size according to the space allotted for the playing of the game. Ordinarily it may have the same dimensions as a regular pool table and the players will then shoot 100 the darts at the target from a distance of about fifteen feet or more or less as desired. Each of the darts is chalked at its end 7 before being projected at the target by the player and the different players use chalks 105 of distinctive colors.

If the dart or cue 5 strikes within a square, the player is credited with pocketing the ball inscribed therein.

If the dart strikes on a line between two 110 squares the player is credited with pocketing the two balls inscribed therein.

2
 If a dart strikes on or within any one of the circles 4, the player is credited with pocketing all four of the balls in the four squares surrounding that circle 4.

5 The above rules apply only if a ball has not been previously "pocketed" by another player.

If the dart strikes the "cue ball" this play is termed a "scratch".

10 The player projecting a dart into the "one ball" square is entitled to another play.

It is obvious that with slight modifications readily obvious to any one playing the game that practically all the various games 15 of pool may be played with this game.

The chalk marks are generally left upon the target until the game is completed and the distinctive color thereof facilitates scoring 20 of the various players. These chalk marks may be readily erased from the target in the event of error or completion of a game.

I am aware that numerous details of construction may be varied through a wide range

without departing from the principles of this invention, and I therefore do not pur- 25 pose limiting the patent granted otherwise than necessitated by the prior art.

Claims.

1. A game comprising a representation of 30 a pool table having squares representing the pool balls, and projecting means for distinctively marking said table to determine an individual play.

2. A game comprising a plurality of targets representing a pool table, and a dart having a non-penetrating cushion point adapted to be permeated with chalk for marking a struck target.

In testimony whereof I have hereunto sub- 40 scribed my name in the presence of two sub-
scribing witnesses.

OCTAVE J. ST. PIERRE.
